UNITED STATES PATENT OFFICE

155,632

DESIGN FOR A PITCHER

Lawrence H. Russell, Saginaw, Mich.

Application July 28, 1947, Serial No. 140,560

Term of patent 3½ years

(Cl. D44—21)

To all whom it may concern:

Be it known that I, Lawrence H. Russell, a citizen of the United States, residing at Saginaw, in the county of Saginaw and State of Michigan, have invented a new, original, and ornamental Design for a Pitcher, of which the following is a specification, reference being had to the accompanying drawings, forming part thereof.

Fig. 1 is a side view of a pitcher showing my new design;

Fig. 2 is a top plan view thereof;

Fig. 3 is a fragmentary view in vertical section showing the shape of the wall of the pitcher, Fig. 1, intermediate the handles thereof, the section being taken in the plane defined by the broken lines in Fig. 1.

I claim:

The ornamental design for a pitcher, as shown.
LAWRENCE H. RUSSELL.
